CHARLES CARR, OF BOSTON, MASSACHUSETTS, ASSIGNOR TO JAMES BENNETT
FORSYTH, OF SAME PLACE.

DESIGN FOR A MAT.

Design No. 20,106, dated August 26, 1890.

No. 20,106.

Patented Aug. 26, 1890.

UNITED STATES PATENT OFFICE.

CHARLES CARR, OF BOSTON, MASSACHUSETTS, ASSIGNOR TO JAMES BENNETT FORSYTH, OF SAME PLACE.

DESIGN FOR A MAT.

SPECIFICATION forming part of Design No. 20,106, dated August 26, 1890.

Application filed March 31, 1890. Serial No. 346,084. Term of patent 14 years.

To all whom it may concern:

Be it known that I, CHARLES CARR, of Boston, in the county of Suffolk and State of Massachusetts, have invented and produced 5 a new and original Design for the Ornamentation of Mats, &c., of which this description and the photographic representation accompanying is a full specification.

The distinctive features of this design are 10 first, a central panel, the ornamentation of which consists of a series of minute triangular pyramids. The disposition of these pyramids upon the surface is that resulting from three series of parallel V-shaped grooves, one running longitudinally, the other two in diverse diagonal directions, the pyramids being formed at the intersections of these grooves or valleys. This configuration is displayed on the central panel and is inclosed by a slight raised line 15 or rim of a cross-section similar to the vertical section of one of the pyramids. Beyond and outside of the raised line or rim extends

an ornamented border of considerable width. The outer margin of the border is ornamented with a series of straight V-shaped grooves, 25 forming between them corresponding inverted V-shaped lines or ridges. Between these and the raised line around the central panel are arranged diagonal raised figures, the angle of these diagonal figures being reversed at 30 the middle of both sides and ends. These diagonals are alternated clusters of straight raised lines and single straight lines, raised and widened at several points into circular spots. The ground-work between these diagonals is a slightly-roughened surface, or smooth 35 and plain if preferred.

I claim—

The design for a mat, substantially as herein described and shown.

CHARLES CARR.
